UNITED STATES PATENT OFFICE

2,462,637

SHARPENING DEVICE

William H. Haydon, Arlington, Va.

Application May 8, 1947, Serial No. 746,650

4 Claims. (Cl. 51—211)

1

The present invention relates to a general utility sharpening device.

The primary object of the present invention is to provide a sharpening device constructed for selective employment with a plurality of elements each carrying a sharpening surface of a different character.

Another object is to provide a sharpening device of light-weight material, and of simple and inexpensive construction, and having a base plate or shield of such shape and dimensions so as to guard the operator's hand against accidental contact with a knife edge during the knife sharpening operation.

In one of its broad aspects, the invention embraces a sharpening device comprising, a base plate or shield provided with a recessed portion, a handle on the opposite side of the base plate or shield from said recessed portion, and an element carrying a sharpening surface for removable engagement in the recessed portion of the base plate.

In general, the invention relates to a sharpening device including a shield with a sharpening element on one side thereof and a handle on the opposite side.

Other and further objects and advantages of the present invention will be apparent from the following description thereof, and from the claims appended thereto.

In the drawing wherein like numerals refer to like or corresponding parts throughout the several views,

Figure 1 is a top plan view of the sharpening device embodying the features of the present invention.

Figure 2 is a side elevation of the sharpening device shown in Figure 1.

Figure 3 is a sectional view taken along the line 3—3 of Figure 1, in the direction of the arrows.

Figure 4 is a sectional view taken along the line 4—4 of Figure 1, in the direction of the arrows, and

Figure 5 is a perspective view of a modified form of the element carrying a sharpening surface, wherein a different sharpening surface is employed.

Referring now to the drawing, the numeral 10 generally represents a base plate or shield of oval configuration. The base plate or shield 10 may be composed of any suitable material, such as stainless steel, plastics, or the like. The base plate 10 may likewise be of any desired shape or size, but it is preferred to make it oval, as shown in Figure 1.

2

The base plate 10 is provided with a recessed or cut-out portion indicated by the numeral 11. The recessed or cut-out portion 11 may be of any desired shape, but it is preferred that it be rectangular in shape, as shown in Figure 1. The recessed portion is cut away at one wall thereof, as illustrated by the numeral 12. An element 13 is adapted for removable engagement in the recessed or cut away portion 11 of the base plate or shield 10, and is provided with a sharpening stone 14 which is cemented or glued to the upper surface thereof. The element 13 is preferably composed of wood, but may be made of any desirable material, such as plastic.

15 The rectangularly shaped element 13 has a spring member 15 disposed at one end thereof for engagement against the end wall of the recessed portion 11, so as to hold the element 13 and the stone 14 tightly within the said recessed portion 11 during the sharpening operation. A handle 16 is secured to the base plate 10 on the opposite side from said recessed portion 11 and is preferably curved in construction so that it may be easily and firmly gripped by the operator during the 20 sharpening operation. The handle portion 16 is disposed diagonally with reference to the longitudinal axis of the recessed portion 11 and the element 13, so that the device may be suitably gripped for an easy sharpening operation, minimizing the danger of being accidentally cut from a knife edge.

The base plate 10 is apertured at 17 to provide means for hanging the general utility sharpening device in a kitchen, or the like.

35 Referring now to Figure 5, there is shown a modified form of the sharpening element comprising a wood block 13a having secured thereto a leather strap 14a. A spring 15a is secured to one end of the rectangularly shaped sharpening element, and is employed in the same manner as the spring 15 to hold the block 13a within the recess 11 of base plate 10. If it is desired to remove the block 13 from the base or shield plate 10, the operator inserts his thumb in the cut away 40 portion of the recess 11 and pushes against the tension of the spring 15 and then lifts the block 13 vertically until it is removed from the recess 11. The block 13a, if it is desired, can then be inserted in the recess 11 of the base plate 10.

45 As pointed out, it is the primary purpose of the present invention to provide a sharpening device of general utility which may be employed with a plurality of sharpening surfaces depending upon the particular device being sharpened. 50 For example, if it is desired to sharpen a knife,

or the like, the stone 14 may be employed as the sharpening surface. If it is desired to sharpen razor blades, or similar thin steel material, the sharpening surface 14a, which is leather, is more desirable. Likewise, other sharpening elements may be employed, as for example steel, if it is desired.

Various modifications of the present invention will be apparent to those skilled in the art without departing from the spirit thereof, and it is therefore desired to be limited only by the scope of the appended claims.

What I claim is:

1. A sharpening device comprising, a base plate having a longitudinally extending recess therein terminating a substantial distance from the margins thereof, an abrasive member fitted firmly in said recess and extending above the top surface of the base plate, a handle member on the side of the base plate opposite to the recess adapted to be grasped by the fingers of the operator with the base plate extending over the operator's hand and wrist to shield them from accidental contact with a tool being sharpened.

2. A sharpening device comprising a base plate having a length greater than its width and having a longitudinally extending recess therein of a length and width substantially less than that of the base plate to provide shielding portions on the base plate for protecting the hand and

wrist of the user, a sharpening element fitted snugly in said recess, and a handle on the opposite side of the base plate from said recess.

3. A sharpening device comprising an oval shaped base plate having a recess therein extending in the direction of the major axis of the base plate and having a length and width less than the base plate to provide a shielding portion on the base plate for the hand and wrist of the user, a sharpening element snugly mounted in said recess, and a handle on the opposite side of the base plate from said recess and sharpening element and disposed diagonally with reference to the major axis of the base plate.

4. A sharpening device as claimed in claim 3 characterized by the fact that the sharpening device is provided with a spring for engaging an end wall of the recess to removably retain the sharpening element within the recess.
